UNITED STATES PATENT OFFICE.

JAMES W. ALSTOTT, OF FORT DODGE, IOWA, ASSIGNOR OF ONE-HALF TO ARTHUR EARL,
OF FORT DODGE, IOWA.

ADVERTISING-DISPLAY DEVICE.

Application filed June 28, 1922. Serial No. 571,342.

To all whom it may concern:

Be it known that I, JAMES W. ALSTOTT, a citizen of the United States, and a resident of Fort Dodge, in the county of Webster 5 and State of Iowa, have invented a certain new and useful Advertising-Display Device, of which the following is a specification.

The object of my invention is to provide an advertising display device of simple, durable and comparatively inexpensive construction.

More particularly my invention relates to a display device including a three sided frame which is so mounted that it may 15 easily rotate, each of the sides of the frame having door members thereon arranged with transparent members so that advertisement placed thereunder will be displayed.

Still another object is to so arrange the 20 device that the advertising matter thereon will not become destroyed, regardless of weather conditions.

With these and other objects in view, my 25 invention consists in the construction, arrangement and combination of the various parts of my device, whereby the objects contemplated are attained, as hereinafter more fully set forth, pointed out in my claim, and illustrated in the accompanying drawings, 30 in which:

Figure 1 is a perspective view of my improved advertising display device, parts being broken away to better illustrate the construction.

Figure 2 is a horizontal sectional view 35 taken on line 2—2 of Figure 1; and

Figure 3 is a sectional view taken on line 3—3 of Figure 2.

In the accompanying drawings, I have 40 used the reference numeral 10 to indicate generally, a weighted base which is provided with a central screw threaded opening 11.

Mounted within the screw threaded opening 11 is a vertical shaft 12. The base 10 is quite heavy so to provide a firm footing 45 for the entire display device.

The display device consists of a triangular shaped frame A. The frame A consists of the corner upright members 13 which are 50 connected together at their upper and lower ends by means of the cross pieces 14.

In order to reinforce the frame A, I provide the reinforcing bars 15, 16, and 17, which are mounted at the upper and lower 55 ends of the frame A. Each of the rein-

forcing bars are arranged to have one end rest against one of the uprights 13 and to have its other end rest midway between one of the cross pieces 14.

From the construction of the parts just 60 described it will be seen that the arrangement of the reinforcing bars 15, 16, and 17, is such that they will cross in a common point.

Extended through each of the reinforcing 65 bars 15, 16, and 17 is an opening through which is extended the shaft 12, as clearly shown in Figure 3 of the drawings.

Directly below the reinforcing bar 16 on the lower end of the frame A, is a ball bearing race 18. Below the ball bearing race 18 70 on the shaft 12 is a collar 19, having a set screw 20 therein.

A plate 21 is mounted on the upper reinforcing bar 17, which has an opening there- 75 in of substantially the same size as the shaft 12, so as to prevent any wear on the reinforcing bar 17.

It will be seen that by shifting the position of the collar 19 on the shaft 12, that I 80 am able to raise the entire frame member A or lower it as desired. The providing of the ball bearing race 18 permits easy rotation of the frame member A.

Each of the cross pieces 14 and the up- 85 rights 13 are provided with a shoulder 22 which receives a composition board 23. The composition board 23 is preferably formed of some material in which a thumb tack may be easily embedded.

The composition board 23 is designed to 90 have advertising matter secured thereto. On each of the corner uprights 13 is the molding 24.

Door members 25 having a glass 26 mounted thereon are hinged to the molding 24 by means of the hinges 27. Fastening devices 28 are arranged on the doors 25 and on the molding 24 for holding the door in proper locked position.

By arranging advertising matter on the composition board 23 and then closing the doors 25, I am able to successfully display the advertising matter without the danger of it becoming spoiled in inclement weather.

My device is especially arranged so that it will rotate on the shaft 12 and in view of the fact, that it is triangular in cross section, the wind will cause it to rotate rather than upsetting it.

Secured to the upper cross piece 14 is a plate member 29, which has fixed to it the pyramid shaped cap 30. The cap 30 is provided with a horizontal flange 31 which rests upon the plate 29 and with a downwardly extending flange 32, which rests against the outer edge of the plate 29, as clearly shown in Figure 3 of the drawings.

The plate 29 extends out beyond the sides 10 of the device so as to form eaves to such an extent that any dripping of water from the cap 30, onto the display device proper, will be substantially eliminated.

It will be seen that my device is very simple and forms a very efficient advertising device.

Some changes may be made in the construction and arrangement of the various parts of my invention, without departing 20 from the real spirit and purpose of my invention, and it is my intention to cover by my claim, any modified forms of structure or use of mechanical equivalents, which may be reasonably included within their scope.

I claim as my invention:

In an advertising display device, a base, a supporting shaft and a frame rotatably supported thereon, said frame comprising three corner posts equidistantly spaced from each other and from the supporting shaft, 30 said posts being connected by inner cross strips at their upper and lower ends, rabbed depressions in the inner edges of the outer faces of said cross strips and of the corner posts, moulding pieces fixed to the outer faces of the cross strips and corner posts and covering the rabbed depressions so as to form inwardly opening slots, panel members received in said slots, door members hinged to the moulding pieces on the 40 corner posts and adapted to fit within the inner outline of the moulding strips, and cross braces extending from each of said corner posts to the cross strips of the side opposite each of said posts.

Des Moines, Iowa, May 23, 1922.

JAMES W. ALSTOTT.
